UNITED STATES PATENT OFFICE.

JAMES MADISON PARKS, OF RAINEY'S CREEK, TEXAS.

IMPROVEMENT IN APPARATUS FOR WIRING PICKET-FENCES.

Specification forming part of Letters Patent No. **147,968**, dated February 24, 1874; application filed September 13, 1873.

To all whom it may concern:

Be it known that I, JAMES M. PARKS, of Rainey's Creek, in the county of Coryell and State of Texas, have invented a new and valuable Improvement in Wiring Picket-Fences; and I do hereby declare that the following is a full, clear, and exact description of the construction and operation of the same, reference being had to the annexed drawings making a part of this specification, and to the letters and figures of reference marked thereon.

Figure 1 of the drawings is a representation of a vertical section of my improvement in devices for wiring picket-fences. Fig. 2 is a top view of same.

This invention relates to that class of building apparatus in which a movable anchor or weight is used as a wire-stretcher in advance of the work, and is designed to furnish means of a very simple character for holding the wires tight and at a given height while applying the pickets and their posts.

In the annexed drawing, A represents a trench, which is of proper width and depth, and of any desired length, and in the center of which post-holes *a* are made, at proper distances apart to receive the posts *J* which sustain the pickets *J'*. *B* is a carriage. It consists of two wheels, *b b*, on an axle, *c*, a draft-tongue, *b¹*, secured between the axle and a bar, *c'*, a guide, *n*, which rises from the tongue *b¹*, and keeps the two wires *h h* separated and in proper line with the posts *J*, a stake, *b²*, which enters the bottom of the trench *A*, and holds the carriage *B* in its proper place astride the trench, and a standard, *d*, which is adjustably secured to the axle and bar *c'*, and between whose upper ends, on a roller, *e*, the two wires *h h* pass. Standard *d* is vertically adjustable when pins *d'*, which hold it in place, are removed. *D* represents a drag, which is composed of a large log, *D*, trimmed to lie in the trench *A*, and provided with a clevis, *g*, and four diverging legs, *g'*, carrying on their upper ends four transporting-wheels, *i*.

The first post *J* is set into the ground very securely, and braced in any convenient manner. The carriage *B* is then moved astride the trench and near the post, and the wires *h h* are passed around it at a proper height, thence through the forked end of the adjustable standard *d*, and on opposite sides of the vertical guide *n*. From this guide the wires are carried along

the trench any required distance, and secured to the clevis *g* at the front end of the drag *D*. This drag *D* is held in place so as to keep the wires under proper tension by loading it down with logs, which are placed between the diverging legs *g'*, like logs on a saw-buck. The carriage *B* is then moved about fifteen feet from the first post, keeping the standard *d* vertically over the trench, and the stake *b²* forced into the ground between the sides of the trench a sufficient distance to prevent the carriage moving backward as the wire is taken up by the introduction of the pickets.

The man who sets the pickets should be on the right-hand side of the wire, facing forward, and on this side should also be the pickets. The man who crosses the wires after each insertion of a picket should stand on the left-hand side of the wires, and, after crossing the same, should draw them apart while the opposite man inserts the pickets. When a post-hole, *a*, is reached, a post is inserted therein, and the wires drawn around a notch cut into it at the proper height, after which this post is firmly fixed into the ground, the carriage *B* is moved off a proper distance, and the work proceeded with, as before stated.

When the fence is made to within about thirty or forty feet of the drag *D*, a post is fixed firmly into the ground in a hole, *a*, and two or three pickets are worked into the wire beyond it, when the wires may be loosened from the drag, and more wires hitched on to continue the work. The drag is then unloaded and turned over upon its wheels, when it can be easily rolled to the point desired and again applied in the trench, as before described.

What I claim as new, and desire to secure by Letters Patent, is—

1. An apparatus for the construction of wired picket-fences, consisting of the standard-guide *d*, guide *n*, and stake *b²*, applied to a carriage, *B*, as and for the purpose described.

2. The reversible drag *D*, with its legs *g'*, rollers *i*, and clevis *g*, as and for the purposes described.

In testimony that I claim the above I have hereunto subscribed my name in the presence of two witnesses.

JAMES MADISON PARKS.
